BOBBIN DELIVERY CRADLE FOR WEFT
REPLENISHING LOOMSWilliam A. Blanchard, Millbury, Mass., assignor
to Crompton & Knowles Loom Works, Worcester, Mass., a corporation of Massachusetts

Application October 4, 1946, Serial No. 701,271

7 Claims. (Cl. 139—245)

1

This invention relates to improvements in bobbin delivery cradles for looms and it is the general object of the invention to provide an improved construction by which cradles for different lengths of bobbins can be made by varying only one of the component parts.

Multicolor weft replenishing looms customarily employ a stationary magazine having vertical stacks of bobbins at the lower end of which is a bobbin delivery cradle. This cradle is mounted for oscillation about a horizontal axis by mechanism forming part of the magazine and called into action preparatory to transfer of a fresh bobbin into a shuttle having an exhausted supply of weft. Heretofore cradles have been made as castings with their bobbin butt and tip engaging parts so constructed that it has been necessary for the manufacturer to keep on hand a large variety of patterns for cradles of different lengths.

It is an important object of the present invention to make the cradles of a substantially straight bar which may be cut the appropriate length and have attached to one end thereof a bearing member formed as a tip support, having at the other end a second bearing member and a butt support so made that it can be secured to the bar at the desired location between the bearings.

Bobbin magazines usually are provided with an inclined guide which directs a released bobbin toward a support leading to a transfer position. In order to insure correct arrival of the bobbin in its transfer position it is desirable that it be delivered smoothly from the cradle. To effect this last named result it is a further object of the invention to provide the cradle with a butt delivering member or guide made of resilient sheet metal which will engage the bobbin support and be held firmly against it to enable the bobbin butt to slide freely from the cradle onto the support.

With these and other objects in view which will appear as the description proceeds, my invention resides in the combination and arrangement of parts hereinafter described and set forth.

In the accompanying drawings, wherein two forms of cradles are illustrated,

Fig. 1 is a side elevation of a multicolor weft replenishing magazine as viewed from the center of the loom showing the improved cradles forming the subject matter of this invention.

Fig. 2 is an enlarged detailed rear elevation of the lower part of the magazine looking in the direction of arrow 2, Fig. 1, and showing the lowest bobbin in the rear stack in its cradle and

2

the lowest bobbin in the stack in front of the rear stack supported by its cradle.

Figs. 3 and 4 are enlarged vertical sections on lines 3—3 and 4—4, respectively, of Fig. 2.

Fig. 5 is a perspective view of one of the cradles shown in Fig. 3, and

Fig. 6 is an enlarged vertical section on line 6—6 of Fig. 1.

Referring particularly to Figs. 1 and 2, the magazine M is shown as formed with an inner side plate 10 for the bobbin butts and an outer side plate 11 for the bobbin tips. These plates are spaced and held together by the usual tie-rods not shown herein and provide storage means for reserve bobbins as they await replenishing operations of the loom. In the present instance the magazine is shown as adapted to hold four stacks of bobbins, each stack being associated with a cradle controlling and operating slide 12 mounted for vertical sliding movement on the plate 10. The bottom of each slide 12 is provided with a head 13 having a slot 14 formed as shown in Fig. 1 to receive an operating pin 15 carried by the cradle to be described. As shown particularly in Fig. 6 each slide 12 is provided with upper and lower notches 15 and 16 separated by a wedge 17. The magazine is provided with a spring plunger 18 for each of the slides 12, these plungers each being urged toward their associated slides 12 by a spring 19. Each plunger has a head 20 to enter the notches 15 and 16 to position the slide accurately in either of two vertical positions to which it may be moved by a selector mechanism designated generally at 21.

Ordinarily the slides 12 are in their down position, but when indication of weft exhaustion is initiated, the slide corresponding to the indicating shuttle is raised by the selector 21 and the corresponding wedge 17 moves upwardly along the associated head 20.

At a later time in the operation of the loom the elevated slide is depressed from its raised position, at which time notch 15 of the slide returns to holding relationship with respect to the corresponding spring plunger. The latter acts by reason of the spring 19 to complete down movement of the slide and then hold the latter in a fixed position. In Fig. 1 the rearmost slide 12 at the left is shown up, while the other slides are shown in their down position.

The inside plate 10 is formed with flanges which define guideways for the several stacks of the bobbins, three of these flanges being shown at 25, 26 and 27 in Fig. 3. The bobbins B have butts 28 which move down the guideways by gravity. The bobbin tips 29 move similarly in

50

guideways formed by flanges 30 on the outer plate 11, see Fig. 4.

The inner and outer magazine plates are generally provided with supports down which a released bobbin will roll toward a common transfer position. In Fig. 3 one of these supports is shown at 32 for the bobbin butts, while Fig. 4 shows a bobbin tip guideway 33. These supports 32 and 33 are customarily yieldingly mounted and the front and back supports are so located that when they are in normal position a bobbin will be supported by them for engagement with a transerrer arm 34 during a replenishing operation of the loom. While the drawing shows specifically the rear pair of stacks of the magazine, it is to be understood that similar constructions are used for the forward stacks.

The matter thus far described is of common construction in magazines for multicolor weft replenishing looms and is set forth to indicate the manner in which the cradles forming the subject matter of the invention operate to control movement of bobbins from their stacks toward the bobbin supports and transfer position.

As previously stated each stack of bobbins will have a bobbin controlled cradle which operates to deliver bobbins so they can pass one at a time from the magazine to transfer position. The detailed drawings, Figs. 3 and 4, show two types of cradles for the rear stacks, but it is to be understood that cradles for the front pair of stacks will be similar to those illustrated herein.

Referring first to the rear cradle 40 it will be seen from Fig. 5 that it is made of an elongated straight metallic bar 41 having preferably flat sides 42 on opposite sides of the bar and extending lengthwise of the latter. The bar has secured as by welding to the left or inner end thereof as viewed in Fig. 5 a bearing 43 carrying a pivot 44 to be supported on the inside magazine frame 10. The bearing 43 is provided with one of the previously described pins 15' by which the cradles may be rocked about its axis when the associated vertical slide 12 moves as set forth hereinbefore.

The opposite or outer end of bar 41 has secured thereto a second bearing 45 provided with a second bearing stud 46 coaxial with stud 44 and received by the outer magazine frame 11. Bearing 45 is made of a substantially flat sheet of metal welded to rod 41 and having a bobbin tip notch 47 and having also a bobbin tip engaging surface 48 concentric with the cradle axis.

Secured to bar 41 between the bearings 43 and 45 is a bobbin butt supporting member 50 made preferably of spring sheet metal and having the intermediate part thereof formed with a socket 51 receiving the bar 41. This socket is secured to one of the flat surfaces of the bar 41 in any approved manner, as by rivets 52, although I am not limited to rivets as a means for attaching the butt support 50 to the bar 41.

Extending from one side of the socket 51 is a bobbin support or delivery jaw 55, while a bobbin retaining arm 56 extends from the opposite side of the socket. The tip notch 47 aligns with the space between the jaw 55 and arm 56, and when the cradle is in its normal position indicated in dotted lines at the right of Fig. 3 the tip of the lowest bobbin in the rear stack rests on surface 48 and the butt of the bobbin rests on a surface 57 of arm 56 which is concentric with the cradle axis. Under these conditions the cradle is empty and its associated vertical slide 12 is down.

When the slide 12 rises the cradle rocks in a clockwise direction as viewed in Fig. 3, retaining arm 56 moving from under the bobbin butt and the jaw 55 rising to support it. At the same time the bearing 45 moves in a clockwise direction so that the bobbin tip falls from surface 48 into notch 47. The lowest bobbin is now in the cradle where it will remain until the associated vertical slide 12 is depressed, whereupon the cradle will rock in a counterclockwise direction and surface 57 will move under the butt of the next bobbin above it which now becomes the bottom bobbin of the stack, and the spring jaw 55 will move down into engagement with the bobbin support 32. This return of the cradle to its normal position is accompanied by delivery of the bobbin to the supports 32 and 33, and the bobbin then rolls toward a transfer position under the transfer arm.

Because of the resilience of support or jaw 55 and the action of spring plunger 18 the jaw will be held resiliently against the support 32, thereby insuring a smooth path of delivery of the bobbin from the cradle to the support. The surfaces 48 and 57 are concentric and move smoothly under the bobbin next to be supported thereby.

In the form of cradle 60 shown at the upper left hand part of Fig. 3 for the bobbin stack immediately in front of the rearmost stack the rod 41 is the same as rod 41 of cradle 40. This cradle has an outer bearing 61 corresponding to bearing 45 and formed with a surface 62 concentric with the axis of cradle 60 as defined by support stud 63 as bearing 61. A bobbin tip pocket 64 in bearing 61 corresponds in function to notch 47. The inner end of cradle 60 is provided with a second bearing 65 having one of the pins 15' and having also a bearing stud 66 corresponding to stud 44 and coaxial with stud 63.

The bobbin butt support 68 of cradle 60 is of somewhat different shape from that shown in Fig. 5, but it nevertheless has a socket 69 extending partly around its rod 41 and secured thereto against one of the flat sides of the rod. Support 68 has a bobbin retaining arm 70 and a bobbin delivery arm 71 which is much shorter than jaw 55. Arm 70 has a bent part defining a surface 72 concentric with the axis of cradle 60 and surface 62.

This second cradle 60 when in normal position is empty and is as shown in full lines in Fig. 3. When it rocks to receive a bobbin it turns in a counter-clockwise direction the effect of which is to move the support arm 71 to a position in which the lowest bobbin of the stack will fall on it and be supported thereby. When the cradle has its reverse or clockwise rocking movement the supporting arm 71 returns to the left, thereby allowing the bobbin to drop, and the retaining arm 70 and its surface 72 moves under the next bobbin above.

From the foregoing it will be seen that I have provided a simple form of bobbin delivery cradle which lends itself to manufacture for use with bobbins of different lengths. The inner and outer bearing and also the butt delivery part of the cradle will be the same for all lengths of bobbins, the only difference for adaptation to bobbins of different lengths being length of rod 41. In both instances the butt support is made preferably of resilient sheet metal formed with a socket to fit the bar or rod 41. The cradles are provided with surfaces 57 or 72 concentric with their axes so that the bobbin retaining arms can slide smoothly under the superposed bobbins of

the associated stack. In the form of cradle shown in Fig. 5 the delivery jaw by reason of its resilience can be pressed against the support 32 by a force derived from the plunger spring 19 to thereby insure smooth delivery of the bobbin from cradle 40 onto support 32. In both forms of the cradle the retaining arm has a relatively long bobbin supporting surface concentric with the cradle axis.

Having thus described my invention it will be seen that changes and modifications may be made therein by those skilled in the art without departing from the spirit and scope of the invention and I do not wish to be limited to the details herein disclosed, but what I claim is:

1. In a bobbin magazine for a weft replenishing loom, an inclined bobbin guideway to direct a bobbin toward transfer position, an oscillatable cradle mounted on the magazine rocked in one direction to receive a bobbin and then rocked in the opposite direction to discharge the bobbin toward the guideway, and a resilient bobbin engaging member on the cradle positioned to engage the guideway when the cradle is rocked in said opposite direction to provide a smooth path of travel for the bobbin from the cradle to the guideway.

2. In a bobbin magazine for a weft replenishing loom, an inclined bobbin guideway to direct a bobbin toward transfer position, an oscillatable cradle mounted on the magazine rocked in one direction to receive a bobbin and then rocked in the opposite direction to discharge the bobbin toward the guideway, and a sheet metal spring member secured to and moving with the cradle and having a part which engages said guideway when the cradle rocks in said opposite direction to provide a smooth path of travel for the bobbin from the cradle to the guideway.

3. In a bobbin magazine for a weft replenishing loom, an inclined bobbin guideway to direct a bobbin toward transfer position, an oscillatable cradle mounted on the magazine rocked in one direction to receive a bobbin and then rocked in the opposite direction to discharge the bobbin toward the guideway, said cradle including an elongated bar having a flat side extending lengthwise thereof, and a sheet metal member extending partly around said bar and secured thereto and held against said flat side to prevent relative angular movement thereof with respect to the bar, said member having a bobbin support movable toward said guideway when said cradle rocks in said opposite direction.

4. A bobbin delivery cradle for a weft replenishing loom, said cradle comprising a substan-

tially straight rod extending for the length of the cradle, a bearing member secured to one end of the rod and having a bobbin tip receiving notch, a second bearing member coaxial with the first member and secured to the other end of the rod, and a bobbin butt support having a bobbin delivery part, a bobbin retaining part formed with a surface substantially concentric with the axis of the bearing members, and a third part

10 intermediate the first two parts secured to said rod between said bearing members.

5. A bobbin delivery cradle for a weft replenishing loom, said cradle comprising a substantially straight rod extending for the length of the cradle, a bearing member secured to one end of the rod and having a bobbin tip receiving notch, a second bearing member coaxial with the first member and secured to the other end of the rod, and a bobbin butt support formed of sheet metal having an intermediate part attached to said rod between said bearing members, a bobbin delivery part extending from one side of the intermediate part, and a bobbin retaining part extending from the opposite side of the intermediate part and having a bobbin butt engaging surface concentric with the axis of the bearing members.

6. A bobbin delivery cradle for a weft replenishing loom, said cradle comprising a substantially straight rod extending for the length of the cradle and having a flat surface along one side thereof, a bearing member secured to one end of the rod and having a bobbin tip receiving notch, a second bearing member coaxial with the first member and secured to the other end of the rod, and a bobbin butt support having a bobbin delivery part, a bobbin retaining part formed with a surface substantially concentric with the axis of the bearing members, and a third part intermediate the first two parts secured to said flat surface of said rod between said bearing members.

7. A bobbin delivery cradle for a weft replenishing loom, said cradle comprising a substantially straight rod extending for the length of the cradle, a bearing member secured to one end of the rod and having a bobbin tip receiving notch, a second bearing member coaxial with the first member and secured to the other end of the rod, and a bobbin butt support having a bobbin delivery part, a bobbin retaining part formed with a surface extending angularly around the axis of the bearing members, and a third part intermediate the first two parts secured to said rod between said bearing members.

WILLIAM A. BLANCHARD.
